SANITARY TOILET APPLIANCE

Newell B. Benson, Baltimore, Md.

Application November 1, 1933, Serial No. 696,271

8 Claims. (Cl. 4—247)

This invention relates to sanitary appliances and special reference to a sanitary seat appliance for water closets.

One important object of this invention is to provide a novel seat appliance in which the seat is formed by spaced rolls covered with paper.

A second important object of the invention is to provide novel means whereby fresh paper is made available each time the seat is used.

10 A third important object of the invention is to provide a novel arrangement of spaced paper covered rolls for this purpose having actuated means for feeding used paper off the rolls.

15 A fourth important object is to provide novel means for severing the used paper from the supply of paper.

20 A fifth important object of the invention is to provide a novel arrangement of this kind wherein the used and severed paper is disposed of automatically and without the necessity of handling such paper.

25 With the above and other objects in view, as will be presently apparent, the invention consists in general of certain novel details of construction and combinations of parts hereinafter fully described, illustrated in the accompanying drawings and specifically claimed.

In the accompanying drawings like characters indicate like parts in the several views, and:—

30 Figure 1 is a plan view, partly in section showing the general arrangement of the invention.

Figure 2 is a front elevation of the device with the front wall of the casing removed.

Figure 3 is a section on the line 3—3 of Figure 2.

Figure 4 is a detail section of the upper part of the invention on the line 4—4 of Figure 1.

Figure 5 is an enlarged detail section, partly broken away, on the line 5—5 of Figure 1.

40 Figure 6 is an enlarged detail section on the line 7—7 of Figure 1.

Figure 7 is an enlarged section on the line 7—7 of Figure 4.

45 In the present illustration of the invention there is disclosed the usual water closet bowl 10 having a rearward extension 11. The usual seat is removed and the present invention is utilized in place thereof. The invention itself includes a rear frame bar 12 extending transversely of the 50 rear part of the bowl and having rearwardly extending feet 13 resting on the extension 11 and secured thereto by bolts 14. Bearings 15 on the feet 13 support a shaft 16 and on one end of this shaft is fixed a sprocket wheel 17. Bevelled gears 55 18 are fixed on the shaft and mesh with similar

gears 19 fixed on shafts 20 having their rear portions journaled in bearings 21 at the ends of the bar 12. The forward ends of the shafts 20 are journaled in bearings 22 formed on the ends of a front frame bar 23 which has its central portion resting on the front of the bowl 10. Each shaft 20 has a drum 24 fixed thereon between the bearings 21 and 22.

5 Rotation of the shaft 16 in the direction of the arrow A (Figure 3) will cause the drums to rotate 10 in the directions shown by the arrows B in Figure 2.

A casing 25 surrounds the water closet and covers the gearing at the rear of the device. This casing is provided internally with a supporting frame 26. Idler sprockets 27 are mounted 15 at the front and rear of this casing adjacent the bottom thereof. A third idler sprocket 28 is mounted in the casing directly above the front sprocket 27 and to the rear of this sprocket 28 20 is a fourth idler sprocket 29.

A endless sprocket chain 30 is led around the sprocket 17 and the idler sprockets as shown in Figure 3 so that this chain has a vertical portion 31 at the front of the casing. A bracket 32 25 is fixed to the rear portion of the frame 26 and a lever 33 has its rear end pivoted to this bracket and extends forwardly through a suitable vertical slot in the front wall of the casing 25.

30 A pedal 34 is carried by the projecting end of the lever and a spring 35 normally holds the lever in raised position. A pawl 36 is pivoted on a stud 37 fixed to the forward part of the lever 33. A spring 38 normally holds this pawl in engagement with the vertical run 31 of the chain 30 so that depression of the lever 33 causes movement of the chain in the direction of the arrow A while in the lifting of the lever by the spring 35 the pawl rides over the chain. Thus, each time the pedal 34 is stepped on and forced downwardly 40 the drums will be rotated in the directions of arrows B.

45 Rolls 39 of a suitable grade of paper are held in the lower part of the casing and paper from these rolls is led up to the outer sides of the drums 24, over the tops of the drums and down the inner sides. Idler rolls 40 mounted on spring arms 41 serve to press the paper firmly against the drums and cause proper feeding of the paper as the rolls are rotated.

50 Hinged plates are provided at the sides of the casing permitting access to the paper compartment. Extending between the frame bars 12 and 23 are fixed knife blades 42 which carry guide fingers 43 entering grooves 44 in the drums 24 55

so that the paper is guided over the tops of the blades 42.

- Above and in cooperation with the blades 42 are vertically movable blades 45 having ends 5 which enter slots 46 in the frame bars 12 and 23. Springs 47 in these slots hold the blades 45 normally spaced above the blades 42 so that the paper may pass freely between each pair of co-operating blades. Adjusting screws 48 serve to 10 regulate the spacing of the blades. The blades 45 are provided with spring arms 49 carrying idler rolls 50 which press against the paper and assist in ensuring proper feeding thereof and also to hold the paper smoothly on the drums. 15 Each movable blade is provided at each end with an operating lug 51 and these lugs lie in the path of operating fingers 52 carried by the ends of the drums. These fingers are preferably in the form of pins fixed in the drums and having 20 rollers mounted thereon. From an inspection of Figure 1 it will be seen that the central parts of the drums overhang the bowl 10. The ends of the drums are preferably crimped to better grip the paper and prevent tearing thereof.

- 25 Obviously, the cutting edges of the blades may be either horizontal as shown or inclined.

- A guard 53 is secured at 54 to the bar 42 and protects the paper and cutting mechanism from water that might splash from the bowl. A slot 30 55 in the lower portion of the guard permits egress of the used paper.

- A disinfectant may be applied to the seat rollers by means of a wiper 56 in the form of a felt strip which is supported in a trough 57 and held 35 in contact with the rollers by means of springs 58, the trough also serving as a reservoir for the disinfectant. It will be apparent from an inspection of Figure 1 that a supply of disinfectant may be introduced from above at either end of the trough 57.

- 40 As previously stated, depression of the pedal 34 operates the drums which have their upper parts covered with paper and together serve as a seat. Operation of the drums causes the used paper to 45 be rolled off and to pass between the knife blades until the fingers 52 engage the lugs 51 which causes depression of the movable blades and severing of the paper. The severed pieces drop 50 into the bowl 10 and are carried off by the usual flushing operation. Simultaneously, unused paper is drawn from the supply rolls 39 and covers the drums.

- 55 There has thus been provided a simple and efficient device of the kind described and for the purpose specified.

- It is obvious that changes may be made in the form and construction of the invention without departing from the material principles involved. It is not, therefore, desired to limit the invention to the exact form herein shown and described, but it is desired to include all forms which properly come within the scope of the claims.

What is claimed is:

1. A sanitary seat including a pair of spaced 65 drums forming seat sides, paper supply rolls having paper therefrom led over said drums to cover the upper surfaces thereof, gearing operatively connecting said drums, a fixed and a movable paper shearing blade associated with each drum, 70 means effecting operation of the movable shear blades upon operation of said drums, said drums being provided with circumferential grooves, and guide fingers carried by the fixed blades and entering said grooves to guide paper from the drums 75 over the fixed blades.

2. A sanitary seat including a pair of spaced drums forming seat sides, paper supply rolls having paper therefrom led over said drums to cover the upper surfaces thereof, gearing operatively connecting said drums, a fixed and a movable 5 paper shearing blade associated with each drum, means effecting operation of the movable shear blades upon operation of said drums, spring means normally holding the movable blades spaced from the fixed blades, adjusting screws opposed to said 10 spring means and limiting the spacing of said blades, said drums being provided with circumferential grooves, and guide fingers carried by the fixed blades and entering said grooves to guide paper from the drums over the fixed blades. 15

3. A sanitary seat including a pair of spaced drums forming seat sides, paper supply rolls having paper therefrom led over said drums to cover the upper surfaces thereof, gearing operatively connecting said drums, a fixed and a movable 20 paper shearing blade associated with each drum, means effecting operation of the movable shear blades upon operation of said drums, spring means normally holding the movable blades spaced from the fixed blades, adjusting screws opposed to said 25 spring means and limiting the spacing of said blades, said drums being provided with circumferential grooves, guide fingers carried by the fixed blades and entering said grooves to guide paper from the drums over the fixed blades, and 30 guards covering the shearing mechanism to protect the same from injury.

4. A sanitary seat including a pair of spaced drums forming seat sides, paper supply rolls having paper therefrom led over said drums to cover 35 the upper surfaces thereof, gearing operatively connecting said drums, a fixed and a movable paper shearing blade associated with each drum, means effecting operation of the movable shear blades upon operation of said drums, spring 40 means normally holding the movable blades spaced from the fixed blades, adjusting screws opposed to said spring means and limiting the spacing of said blades, said drums being provided with circumferential grooves, guide fingers 45 carried by the fixed blades and entering said grooves to guide paper from the drums over the fixed blades, guards covering the shearing mechanism to protect the same from injury, and means for supplying disinfectant to the surface 50 of the seat rollers.

5. A sanitary seat including a pair of spaced drums forming seat sides on opposite sides of a toilet bowl, paper supply rolls having paper therefrom trained over said drums to cover the upper surface thereof, gearing operatively connecting said drums, means for operating said gearing, a fixed and a movable paper shearing blade associated with each drum, fingers projecting from the ends of the drums and laterally extended lugs on the movable blade said lugs being in the path of the fingers when rotated, whereby upon rotation of the drums the fingers coact with the lugs to cause the blades to sever the paper. 55

6. In a device of the class described a closet bowl, a frame supported on the upper edge of the bowl, means for securing the frame rigidly upon the upper edge of the bowl, approximately parallel rollers mounted for rotation on the frame, 70 the rollers being located at the sides of the frame and being disposed above the frame, to constitute a seat which supports the user in vertically spaced relation to the frame, paper supply rolls having paper therefrom trained over 75

the rollers to cover the rollers, gearing operatively connecting the rollers, means for operating the gearing, paper shearing devices associated with the rollers and means for operating the shearing devices.

5. 7. In a device of the class described, a closet bowl provided with openings for the reception of means for hinging a seat to the bowl, the distance between the openings being determined by 10 the distance between the hinge elements that are carried by the seat, a frame resting on the bowl when the seat is removed, the frame having openings registering with the openings of the bowl, attaching elements in the registering openings, and 15 securing the frame rigidly to the bowl, approximately parallel drums mounted for rotation on the frame and providing seat sides, paper supply rolls having paper therefrom trained over the drums to cover the upper surface of the drums,

gearing operatively connecting the drums, means for operating the gearing, paper shearing devices associated with the drums and means for operating the shearing devices.

8. A device of the class described including a 5 pair of spaced drums forming seat sides on opposite sides of a toilet bowl, paper supply rolls having paper therefrom trained over said drums to cover the upper surface thereof, gearing operatively connecting said drums, means for operating said gearing, paper shearing devices associated with the rollers, means for operating the shearing devices, means for guiding the paper from the rolls, and a shield for protecting the guiding and shearing devices from water splashed 10 15 from the bowl, said shield constituting means for guiding the paper into the bowl.
